Primary Examiner—Robert M Spear*Assistant Examiner*—Karen Acker(74) *Attorney, Agent, or Firm*—Bachman & LaPointe, P.C.(57) **CLAIM**

The ornamental design for a flexible sheet material, as shown and described.

DESCRIPTION

FIG. 1 is an enlarged detail view of a flexible sheet material in accordance with the present invention; and,

FIG. 2 is a perspective view of the flexible sheet material.

A specific length forms no part of the claimed design.

FIG. 2

UNITED STATES PATENT AND TRADEMARK OFFICE
CERTIFICATE OF CORRECTION

PATENT NO. : D624,322 S
APPLICATION NO. : 29/282041
DATED : September 28, 2010
INVENTOR(S) : Jörn Schröer

Page 1 of 1

It is certified that error appears in the above-identified patent and that said Letters Patent is hereby corrected as shown below:

Cover Page, Item 75, the Inventor's name should be spelled Joern Schroeer or Jörn Schröer.

Signed and Sealed this
Twenty-eighth Day of June, 2011

David J. Kappos
Director of the United States Patent and Trademark Office
